US00D945447S

(12) **United States Design Patent** (10) **Patent No.:** **US D945,447 S**
Carrigan et al. (45) **Date of Patent:** **** Mar. 8, 2022**

(54) **DISPLAY SCREEN OR PORTION THEREOF
WITH GRAPHICAL USER INTERFACE**

(71) Applicant: **Apple Inc.**, Cupertino, CA (US)

(72) Inventors: **Taylor Gerard Carrigan**, San Francisco, CA (US); **Patrick Lee Coffman**, San Francisco, CA (US); **Christopher P. Foss**, San Francisco, CA (US)

(73) Assignee: **Apple Inc.**, Cupertino, CA (US)

(**) Term: **15 Years**

(21) Appl. No.: **29/759,444**

(22) Filed: **Nov. 23, 2020**

Related U.S. Application Data

(63) Continuation of application No. 29/680,496, filed on Feb. 15, 2019, now Pat. No. Des. 916,867.

(57) **CLAIM**

The ornamental design for a display screen or portion thereof with graphical user interface, as shown and described.

DESCRIPTION

The sole FIGURE shows a front view of a display screen or portion thereof with graphical user interface showing the claimed design.

The peripheral dashed broken lines illustrate a display screen or portion thereof, and form no part of the claimed design. The interior broken lines illustrate portions of the graphical user interface which form no part of the claim design.

The horizontal broken line illustrates a boundary and forms no part of the claimed design and the portion of the graphical user interface above the horizontal dashed broken line, shown in half-tone/deemphasized, forms no part of the claimed design.

1 Claim, 1 Drawing Sheet
